UNITED STATES PATENT OFFICE.

EDWIN T. GOLDSHORPE, OF CHICAGO, ILLINOIS, ASSIGNEE TO ELASTIC PAINT CO., OF CHICAGO, ILLINOIS.

DRYER.

Application filed September 23, 1920. Serial No. 412,321.

To all whom it may concern:

Be it known that I, EDWIN T. GOLDSHORPE, a citizen of the United States, and a resident of the city of Chicago, county of Cook, and 5 State of Illinois, have invented certain new and useful Improvements in Driers, of which the following is a specification.

My invention relates to improvements in driers and has for its object the provision 10 of an improved construction of this character in which various materials may be dried with great convenience and efficiency.

Other objects will appear hereinafter.

The invention consists in the combinations 15 and arrangements of parts hereinafter described and claimed.

The invention will be best understood by reference to the accompanying drawings forming a part of this specification, and in 20 which,

Fig. 1 is a horizontal section of a drier embodying the invention.

Fig. 2 is a vertical longitudinal section of the same.

Fig. 3 is a vertical transverse section of the same.

Fig. 4 is an enlarged detailed view of the feed in end of one of two containers or retorts employed in the drier, and

Fig. 5 is a view at right angles with Fig. 4.

The preferred form of construction as illustrated in the drawings comprises a suitable heating chamber or furnace 6 having 35 retorts or containers in the form of pipes 7 arranged therein. The pipes 7 are arranged parallel to each other and at an inclination to the horizontal, suitable burners 8 being provided in the walls of said heating chamber

40 for heating the same by means of gas or other suitable fuel. At their upper ends the pipes 7 project through the wall of chamber 6 and are provided with scoops 9 having openings 10 at their bases leading 45 into the said pipes. The pipes 7 are geared together at their upper ends, as indicated, to

rotate in opposite directions and are geared to a guide shaft 11 as shown and whereby said pipes will be slowly rotated in opposite 50 directions as will be readily understood. An exhaust hood 12 is positioned above the upper ends of pipes 7 and is equipped with a suitable exhaust fan 12', by means of which steam or other gases emanating from the

55 upper ends of said pipes will be drawn away.

A suitable well or hopper 13 is arranged under the upper ends of the pipes 7 and into and out of which the scoops 9 revolve and pick up material to be dried which is supplied to said well or hopper, said material thus picked up by said scoops being discharged into the upper ends of pipes 7, as will be readily understood. The pipes 7 are mounted at their lower ends to rotate freely and are provided with discharge openings 60 14 arranged over a discharge well 15 having an outwardly inclined bottom 16 and by means of which the material falling from the discharge openings 14 will be discharged from the drier.

In use the material to be dried are supplied to the well 13 and is automatically picked up therefrom by the scoops 9 and discharged into the upper end of pipes 7. The constant rotation of said pipes causes said material 70 to feed downwardly through said pipes, being thoroughly agitated during such downward feed, the moisture or other gases contained therein passing off through the openings 10 and being removed by the exhaust 75 fan 12'. The time during which the material is subjected to this drying action may be varied by varying the speed of shaft 11. When the dried material thus reaches the lower end of pipes 7 it is discharged through 80 the openings 14 into the well 15 from which it may be removed as desired. The drier is especially adapted for use in drying fuller's earth or the like but it may obviously be used for drying other materials.

While I have illustrated and described the preferred form of construction for carrying my invention into effect, this is capable of variation and modification without departing from the spirit of the invention. I, 90 therefore, do not wish to be limited to the precise details of construction set forth, but desire to avail myself of such variations and modifications as come within the scope of the appended claims.

Having described my invention, what I claim as new and desire to secure by Letters Patent is:—

1. In a drier, the combination with a heating chamber, of wells at the opposite 105 ends of said chamber, material carrying elements mounted to rotate in said chamber; and means for feeding material to said elements from one of said wells, said material being discharged from said elements into 110

- the other of said wells by the rotation of said elements, substantially as described.
2. In a drier, the combination with a heating chamber, of wells at the opposite ends 5 of said chamber, material carrying elements mounted to rotate in said chamber; means for feeding material to said elements from one of said wells, said material being discharged from said elements into the other 10 of said wells by the rotation of said elements, and heating elements exposed to the interior of said chamber, substantially as described.
3. In a drier, the combination with a heating chamber, of wells at the opposite ends 15 of said chamber, material carrying elements mounted to rotate in said chamber; means for feeding material to said elements from one of said wells, said material being discharged from said elements into the other 20 of said wells by the rotation of said elements; and gas burners carried by the opposite side walls of said chamber and exposed to the interior thereof, substantially as 25 described.
4. In a drier, the combination with a heating chamber, of wells at the opposite ends of said chamber; material carrying elements mounted in said chamber in parallel relation 30 with respect to each other and adapted to rotate in opposite directions; and a scoop carried by each of said elements adjacent one end thereof for feeding material into said elements from one of said wells, said 35 material being discharged from said elements into the other of said wells by the rotation of said elements, substantially as described.
5. A drier comprising a heating chamber; a rotatable tubular container mounted there- 40 in at an inclination to the horizontal; a scoop carried by the upper end of said container, there being an opening in said container at the base of said scoop adapted to discharge material from said scoop into said container; means for supplying material to said scoop, there being a discharge opening in the lower end of said container; means for rotating said container; and an exhaust hood located over the upper end 45 of said container, substantially as described.
6. A drier comprising a heating chamber; a plurality of pipes arranged in said heating chamber parallel to each other and at an inclination to the horizontal; said pipes 50 projecting at the upper ends through the walls of said heating chamber; scoops carried by the upper ends of said pipes, there being openings at the bases of said scoops leading into said pipes; a supply well under 55 the upper ends of said pipes in operative relation with said scoops; a discharge well under the lower ends of said pipes provided with an inclined bottom leading out of said heating chamber, there being discharge 60 openings in the lower ends of said pipes; and an exhaust hood arranged over the upper ends of said pipes, substantially as described.

In testimony whereof I have signed my 70 name to this specification in the presence of two subscribing witnesses.

EDWIN T. GOLDTHORPE.
